UNITED STATES PATENT OFFICE.

FRANKLIN E. ARNDT, OF GALION, OHIO, ASSIGNOR TO THE GALION IRON WORKS AND MANUFACTURING COMPANY, OF GALION, OHIO.

HOISTING AND DUMPING MECHANISM.

1,154,474.

Specification of Letters Patent. Patented Sept. 21, 1915.

Original application filed April 8, 1914, Serial No. 830,469. Divided and this application filed March 23, 1915. Serial No. 16,397.

To all whom it may concern:

Be it known that I, FRANKLIN E. ARNDT, a citizen of the United States, residing at Galion, in the county of Crawford and State 5 of Ohio, have invented certain new and useful Improvements in Hoisting and Dumping Mechanism, of which the following is a specification.

This application is a division of an application filed by me April 8, 1914, Serial No. 830,469.

The invention relates to hoisting and dumping mechanism, and has special reference to means for preventing material being 15 wasted by scattering from a dumping car into a pit and also has reference to means for covering the pit when the apparatus is not in use.

The invention is illustrated in the accompanying drawings, and will be hereinafter fully described, the novel features being subsequently particularly pointed out in the 20 claim following the description.

In the drawings: Figure 1 is an end elevation of a hoisting and dumping mechanism showing my improvements in position; Fig. 2 is a front elevation of the frame embodying the particular improvements forming the subject-matter of this application. 25

The apparatus to which my invention relates embodies a pit 1 which is provided at the side of a railway track 2 and into which the contents of a dumping car are discharged through a chute 3 having a spout 4 and a cut-off 5. A bucket 6 is mounted upon a cable 7, which cable is secured to a carriage 8 mounted upon a track 9 which is disposed above a bin 10 arranged at a point 30 adjacent the car tracks 2 and into which the material is discharged from the bucket 6.

The several parts of the apparatus thus enumerated may be of any well-known and preferred construction, and the general operation of the same is well known, the material being transferred from the car through the chute 3 and spout 4 to the bucket 6 which is then lifted to the carriage 8 and caused to travel along the track 9 to a position over the bin 10 when it is discharged. The bucket is then returned to its position at the bottom of the pit 1, as will be readily understood. 40

The spout 4 and the cut-off 5 are con-

trolled through levers 11 and 12, respectively, and the said levers are mounted upon a frame above the pit and adjacent the car track and connected with the spout and cut-off respectively by links 13 and 14. The frame upon which the levers are mounted 55 comprises standards 15 and 16, the lower portions of which are connected by boards 17 secured to and extending between the standards and secured upon a base 18 by hinges 19, the said base 18 being disposed 60 upon the ties which form part of the bed of the tracks 2 and being disposed close to the tracks and adjacent the mouth of the pit. It will be readily understood that the standards 15 and 16 are disposed between the 65 track and the pit and in a vertical plane substantially parallel with the track. The levers 11 and 12 are pivoted upon one of the standards and are adapted to be held in their raised positions by being engaged over 70 suitable hooks or other devices, indicated at 75 20, upon the co-acting standards.

It will be readily noted that, inasmuch as the frame, consisting of the standards and the boards 17 secured thereto, is connected 80 to the base by hinges, it may be swung to an upright position, as shown in the drawings, to permit the movement of the bucket into or out of the pit or it may be swung 85 outwardly and downwardly so as to extend over the pit and thereby prevent workmen or persons passing near the pit accidentally dropping into the same and being injured.

The frame will be supported in its upright position by a brace 21 pivoted to the 90 frame and extended down into the pit, the free end of the brace being provided with a notch 22 adapted to engage a pin or stud 23 on the side wall of the pit, as shown in Fig. 1. When the frame is in its upright position, any material which may happen to fall over the side of the dumping car will 95 be prevented from passing into the pit and thereby being lost, it being understood that the several working parts are so arranged 100 that material passing into the pit will not drop into the bucket unless it should be in the vertical plane of the bucket and, consequently, in order to assure material passing 105 into the bucket, it should flow through the discharge spout 4.

The frame herein shown and described is extremely simple in its construction and will

be found highly efficient in use. The operating levers for the cut-off and the spout will, of course, swing with the frame and, if it should happen that the links connecting the levers with the spout or cut-off should be of such length that they will not permit the frame to swing down flat upon the surface of the ground at the sides of the pit, such action would merely increase the value of the frame as a guard to prevent persons falling into the pit, as it would then present more or less of an obstruction to prevent them reaching the pit.

It is, of course, obvious that the levers 11 and 12 are pivoted to the standard 15 and the links which are actuated by the levers are pivotally connected with the same. When the platform is swung over the pit, therefore, the lever 11 may be moved about 20 its pivotal support so as to accommodate

the link 13 to the changed position of the platform.

Having thus described the invention, what is claimed as new is:—

In an apparatus of the character described, the combination of a pit, a base disposed adjacent the mouth of the pit, a frame hinged to the base for movement in a vertical plane relative to the base, a partition wall carried by the said frame, a spout within the pit, a cut-off within the pit, levers mounted upon the frame above the partition wall, and connections between said levers and the cut-off and the spout respectively. 25

In testimony whereof I affix my signature in presence of two witnesses.

FRANKLIN E. ARNDT. [L.S.]
